SAM EVERETT FINLEY, OF ATLANTA, GEORGIA.

MEANS FOR MATURING AND STABILIZING ROAD STRUCTURES.

Application filed June 23, 1926. Serial No. 118,048.

The invention relates to a novel apparatus for maturing and stabilizing road structures, including those made of mineral aggregate and bituminous binding material, which comprises means for subjecting the body of the road structure to a series of alternatively varying pressures progressively applied in a direction substantially normal to the road surface and in parallel spaced zones, and simultaneously imposing oppositely disposed lateral pressures in each zone, whereby the aggregate is worked and kneaded in all directions until it is firmly interlocked and compacted, the larger elements being forced toward the bottom and the progressively finer material filling the voids between the larger elements, and elevated toward the top of the road in the order of their sizes, while the binding medium is rubbed into and thoroughly mixed with the aggregate throughout the road structure, fixing the aggregate as a consolidated mass enveloped and united in a matrix of the binder; these operations and results being effected, preferably, by a novel type of roller having continuous circumferential ribs in spaced relation and of alternately varying heights, with the peripheral face of each rib curved transversely.

In the accompanying drawings,

Fig. 1 is a partial side elevation of a typical road roller having the new form of roller element applied thereto.

Fig. 2 is a front elevation partly in section, of the roller element.

In constructing roadways and the like, of mineral aggregate and bituminous binder, the ultimate desideratum is to obtain a road structure in which the mineral aggregate elements are firmly interlocked, with the larger elements at the bottom and the smaller elements grading off toward the top surface of the road in which the finest aggregate is disposed as the wearing surface, this densified and compacted body of graded aggregate being firmly imbedded in a matrix of bituminous binder. Such a road structure is ideal, in that it is substantially homogeneous and uniform throughout, is water and weatherproof, and, while it is sufficiently resilient to provide a perfect rolling surface for vehicular traffic, it is inherently stable, against the shoving, rolling and scouring effects of such traffic, and altogether approximates a condition of permanence and durability under all conditions of use. All road engineers have striven to attain these highly desirable characteristics in finished roads and it has long been an established canon of practice to cover the prepared subgrade of a road bed with mineral aggregate varying in sizes from the largest to the smallest from the bottom upward and then compact the layer of mineral aggregate, either before or after the application of the binding medium thereto, by means of a heavy roller, usually with a smooth cylindrical surface, or, in some cases, with an interrupted cylindrical surface, such, for example, as would be formed by a series of independently mounted disks, or by a unitary cylinder having circumferential ribs of uniform height spaced at intervals laterally of the roller surface. These various types of rollers, as heretofore employed, have proven ineffective, however, to produce a road structure in which all of the elements of the aggregate are compressed into a dense, compacted, interlocked and substantially uniform mass, for the reason that the pressure applied by the roller is normal to the surface of the road, so that the movement of the aggregate elements is downward and in the direction of movement of the roller, due to the action of the curved surface of the roller shoving elements of the aggregate near the top of the layer ahead of it.

The present invention is designed to effect a thorough kneading and rubbing of the elements of the road structure, during the compacting operation, by initially causing a movement of the elements downwardly, laterally and also in the direction of movement of the roller, so that the elements are firmly interlocked, the larger sizes of the aggregate being forced toward the bottom and the smaller sizes being worked toward the top, after which the compacted structure is subjected to maximum pressure applied in parallel zones over the entire surface, thereby producing a substantially homogeneous mass, the elements of which are practically proof against relative movement in any direction. To produce these results, the preferred instrumentality is that illustrated in the drawings, in which 1 represents the body of the rolling element of a power roller, which may have a weight of ten tons, but which weight may be varied according to the particular type of road being con-

structed. The peripheral surface of the roller element 1 is provided with a series of circumferential ridges or ribs 2 and 3 separated by intervening spaces, these ribs or ridges, which should be continuous, alternate in height, the ribs 3, for example, being approximately two-thirds as high as the ribs 2. The side walls of the ribs are preferably slightly convergent toward the outer periphery, which latter is curved or convexed transversely, so that all of the peripheral surfaces of the ribs are uniformly curved peripherally and transversely, as indicated on the drawings by the surfaces 4 and 5. It will be seen, therefore, that any part of the contact area of the roller 1 is curved in every direction; that is to say, no straight line, however short, would contact this surface at more than one point, with the result that the material of the road surface, which is engaged by these contact surfaces of the ribs, is subjected to alternating varying pressures in a direction substantially normal to the road surface and in parallel spaced zones and to simultaneously imposed oppositely disposed lateral pressures in each zone, as well as to pressure imposed by the forward rolling movement of the surface of each rib. This effects a distinct rubbing, kneading and compressing action upon all of the elements of the road structure to force the latter into most intimate interlocking engagement with a minimum of voids between the aggregate elements. The apparatus may be used effectively in preparing the mineral aggregate base of the road structure, after the latter is distributed on the prepared subgrade, by operating the roller over the surface of the aggregate layer. During the initial movements of the roller, the higher ribs 2 sink into the loose aggregate and force the latter downward and also laterally and forwardly to a slight extent, by the maximum pressure represented by the entire weight on the roller, which is distributed by the peripheral faces of the higher ribs 2. As the roller is moved back and forth over the surface of the aggregate, all portions of the aggregate body are ultimately subjected to this maximum pressure and kneading effect of the ribs until the entire mass of the aggregate is ultimately consolidated and compacted, with the larger elements of the aggregate worked to the bottom and the smaller elements forced toward the top, so that, when the rolling operation is completed, all of the elements of the aggregate body are firmly interlocked and the surface is relatively smooth, dense and uniform. After the foundation of the road bed has been thus prepared, and reduced to a substantially uniform and rigidly keyed or interlocked body of aggregate, ranging from the largest sizes at the bottom to the smallest sizes at the top, the binding medium is

applied, usually in the form of asphalt or bitumen of any suitable character, and finally a top dressing of stone chips, sand or the like, is spread over the surface, which is again subjected to a thorough rolling by the same roller, which has the effect of kneading the binding material into the interstices of the mineral aggregate layer and compacting the surface of the roadway into a dense and uniform wear resisting consistency, that is impossible of attainment with the older types of rollers.

It is to be noted that the action of this particular type of roller is distinctly novel and the results obtained thereby are not approximated by the rollers heretofore employed for this general purpose. On first passing over the more or less loose or uncompacted aggregate, the ribs of the roller sink in the loose aggregate until all of the peripheral surfaces of the roller are in contact with the top surface of the aggregate and the pressure per square inch imposed by the roller is the least possible. The material of the aggregate is rubbed and massaged, due to the divergent diameters of the ribs, kneaded and pushed in all directions and forced into the closest possible contact. All bridging of the aggregate is prevented, the fine material is rubbed into the voids and the coarse non-friable material is forced deeper into the surface, while the finer material and binder is raised and spread in all directions. The density, imperviousness and supporting power of the road structure are thus all increased to a maximum. The peripheral ribs of the roller sink less and less into the surface, as the compacting progresses and finally rides over the surface of the compacted material on a few points of contact represented by the engaging peripheral surfaces of the higher ribs 2, thereby producing a maximum pressure on the road structure at these points of contact, and, as the rolling operation is continued until the entire road surface has been treated, it is apparent that the whole area of the road will ultimately be subjected to the maximum pressure represented by the entire weight of the roller, as distributed by the engagement thereof by the higher ribs. A ten ton roller of the usual cylindrical type ordinarily weighs about two hundred pounds per linear inch of roll. If the area of contact of such a roller were less, as in the ribbed type constituting the present invention, the pressure per square inch upon the road structure would be increased indefinitely and limited only by the moduli of elasticity of the materials in contact.

Many road and street surfaces of the mineral aggregate asphalt binder type require long periods in which to mature and to reach their best effectiveness. This maturing process is aided by the action of traffic, which

performs slowly and in lanes some of the functions which the instant invention produces quickly and uniformly over the full surface of the road. For example, asphalt 5 macadam is usually compacted with a roller weighing approximately two hundred pounds per linear inch of roll and is finished by casting dry stone chips over this surface. Traffic is then turned on and the dry 10 stone gradually imbedded or worn away, while the asphalt and fine material is kneaded to the surface. This maturing by traffic occurs first in traffic lanes, while outside of these lanes the maturing is very slow. 15 In any case, a year or more is usually required to bring the roadway to its best condition. The machine heretofore described, and the method which it carries out, are designed to greatly accelerate the maturing 20 process, while, at the same time, conserving the mineral aggregate and not wasting it in dust produced by the attrition of vehicle wheels. The same rapid maturing and stabilization is accomplished by the use of 25 this method of machine on various other types of road construction. Among these may be included all road types, depending upon a binding medium which is liquid or a combination of liquids, whether these types 30 be hot mix pavements, or those manufactured by the application of bituminous or other binding medium by penetration processes. In the hot mix types, the kneading, working and imbedding process, in combination 35 with large finishing pressure per square inch, produces the most compact and most dense mixture possible. Further, it decreases the perviousness to a minimum and increases the supporting power and stability 40 of the road structure to a maximum. In the penetration types, mutually soluble combinations of liquid bitumens may be used and the elimination of the less viscous bitumen

is hastened by the mechanical action of the roller, as described, while, at the same time, 45 the stability of the remaining bitumen is greatly increased, because of the increased oxidation, and the more rapid release of the lighter molecules, carrying with them entrained heavy molecules, together with the 50 working into the matrix of the more finely divided aggregate. Also, emulsions of bitumen in water are quickly broken under this roller, releasing the water and coalescing the elements of the bitumen. It will be seen, 55 therefore, that the method hereinbefore described and the apparatus by means of which the same is carried out, are most effective not only in preparing and compacting foundations of mineral aggregate, but are 60 also particularly efficacious in rapidly maturing and stabilizing the wearing surfaces of bituminous concrete roadways.

While the invention has been described with particular reference to its application 65 in treating bituminous concrete road structures, it is to be understood that it is not limited to this specific type of road, but evidences a high degree of utility in maturing and stabilizing road structures of clay, 70 gravel, sand, earth, water-bound macadam and other types.

What I claim is:

1. Means for maturing and stabilizing composite road structures, comprising a 75 roller having continuous circumferential ribs in spaced relation and alternately varying heights on its periphery, the peripheral face of each rib being curved transversely.
2. Means for maturing and stabilizing 80 composite road structures, comprising a roller having continuous circumferential ribs in spaced relation and alternately varying heights on its periphery.

In testimony whereof I affix my signature.
SAM EVERETT FINLEY.
